SEAT SPRING

Clare H. Graham, Detroit, Mich., assignor to General Motors Corporation, Detroit, Mich., a corporation of Delaware

Application April 17, 1939, Serial No. 268,159

2 Claims. (Cl. 155—179)

This invention relates to seat springs and particularly seat back springs. In seat back springs, at the present time, it is customary to use a so-called spacing strip between the outer coils of the springs. These spacing strips are intended to hold the trimming material from being pressed or falling in between the coil springs. 5

It has been customary to use burlap strips for this purpose but, in order to give the springs what has been thought to be the necessary freedom of action, it has been customary to use long coil springs in the edges of the burlap and the burlap has been loosely Shirred on these coil springs so as to give the spacing strips a longitudinal yield. It has also been thought necessary to make the spacing strips slightly wider than the distance between the tops of the coil springs so as to give some yield in this direction. 15

The present invention is an improvement over this arrangement in eliminating the long coil springs and therefore making for economy. This is achieved by using short coil springs at each end of the strip for connecting the strip ends to the end rows of coil springs. It has been found 20 that this acts equally well and is very much cheaper to build by reason of eliminating the long coil springs.

In the drawings:

Fig. 1 is a plan view of a seat back spring 30 equipped with my improvement.

Fig. 2 is a top or edge view of the spring shown in Fig. 1.

Fig. 3 is a cross section on the line 3—3 of Fig. 1.

Fig. 4 is a fragmentary plan view showing a modified form.

Fig. 5 is a fragmentary view of another modified form of construction.

The spring seat is provided with the usual border frames 1 and 2. The top and bottom border frames are connected by the hinging diagonals 3. The rear ends of the hour-glass type of springs 4 are supported by the cross members 5. No claim is made to this much of the construction as it is old and conventional. The burlap spacing strip is designated 6 and this is clipped to the top coils of two adjoining rows of springs by hog rings 7. The burlap strip is folded back on the edges to form a hem as at 8. 40 Preferably, the strip is stretched taut as shown in Fig. 3. At each end of the strip, the material is folded over (as shown in Fig. 2) at 8, forming a loop and through this loop is threaded a small coil spring 10 whose ends hook over the end row 50 of the hour-glass type of springs. This permits

the entire strip to yield longitudinally when the load is on the strip and the adjoining springs. I find that this gives all the freedom of action that is necessary and is much cheaper than a spacing strip designed to yield intermediate its length 5 and which has the loose burlap Shirred upon small coiled springs that run the entire length of the strip.

In a seat back spring of normal height, there will ordinarily be four rows of springs and three 10 of my improved spacing strips will be used. But, I find that, if it is desired to add more flexibility where the greatest load comes, two spacing strips can be used between the top and bottom rows of springs and crossed coiled wire springs 11 can be 15 used as spacers for the center rows of springs. This modified form is shown in Fig. 4 of the drawings.

Preferably, coil connecting springs 12 are used between the individual springs of the top row in 20 order to prevent the trimming dropping through these springs at the point where it is curved backwardly. A top spacing strip 13 connects the top coil springs with the top border wire 14.

In Fig. 5, a modified form of construction is 25 shown in which, in place of the hem 8 with the coil spring 10, separate coil springs 15 are hooked in the corners of the burlap spacing strip 6 and also hooked over the top coils of the end springs.

What I claim is:

1. In a seat spring, the combination of border frames, one of the border frames provided with cross members, springs anchored at one end to the cross members and spacing strips of flexible material connecting the springs together at the 35 other ends, the said spacing strips being connected to the end springs of the assembly by a yieldable member, the said connection being in the form of a loop of the material of the spacing strip at each end and a small coil spring threaded 40 through the loop and connected at each end to springs in the end row of springs.

2. In a seat spring, the combination of frames and coil springs supported by one of the frames and having their opposite ends connected with 45 the other border frame, flexible spacing strips having loops in their ends for tying the said ends of the springs to each other, the said spacing strips comprising fabric strips connecting adjacent springs in substantially taut relation, and 50 yieldable means connecting the ends of the taut spacing strips to the end rows of coil springs in the form of small coil springs threaded through loops in the ends of the spacing strips.
